UNITED STATES PATENT OFFICE.

LEE B. JONES, OF EVANSVILLE, INDIANA, ASSIGNOR TO SUNBEAM ELECTRIC MANUFACTURING COMPANY, OF EVANSVILLE, INDIANA, A CORPORATION OF INDIANA.

NUMBER PLATE FOR HEADLIGHTS.

Application filed August 5, 1920, Serial No. 401,535. Renewed October 3, 1923.

To all whom it may concern:

Be it known that I, LEE B. JONES, a citizen of the United States, residing at Evansville, in the county of Vanderburg and State of 5 Indiana, have invented new and useful Improvements in Number Plates for Headlights, of which the following is a full, clear, concise, and exact description, reference being had to the accompanying drawing, 10 forming a part of this specification.

My invention relates to closure members and it has particular relation to members of the character designated which are used to close an opening in a headlight casing, and 15 which embody transparent or translucent members.

One object of my invention is to so form a closure member that the central opening thereof may be closed by a suitable light- 20 transmitting member in a simple and expeditious manner. In furtherance of this object I provide means whereby such a glass, or other light-transmitting, member may be positioned in the aforesaid opening irrespec- 25 tive of the thickness of said member.

For a better understanding of my invention reference may be had to the accompanying drawings, in which:

Fig. 1 is a perspective view of a headlight 30 showing the manner in which a side wall embodying my invention may be positioned;

Fig. 2 is a plan view of the closure member looking at the inside thereof;

Fig. 3 is a plan view of said member showing the outside face thereof;

Fig. 4 is an elevational sectional view taken on the line 4—4 of Fig. 3;

Figs. 5 and 6 are fragmentary, sectional views taken on the lines 5—5 and 6—6, re- 40 spectively of Fig. 2; and

Fig. 7 is a fragmentary, perspective view illustrating the manner in which the side wall frame is formed at a particular portion thereof.

While the hereinafter described and claimed closure member is shown in connection with a headlight, it is understood that the said closure member only is being broadly and specifically claimed in the present application and that the headlight shown forms the subject matter of a separate co-pending application, Serial No. 401,636, assigned to the Sunbeam Electric Manufacturing Company. These two applications 55 comprehend separate and distinct inventive

subject matter and are not related except in so far as my improved closure.

Referring now more particularly to the drawings, same shows a headlight comprising a casing 1 which is provided with a hinged goggle door 2. At either side (one side only of which is shown) of the casing is formed a housing and side opening 3, and a closure member 4 is adapted to be hinged thereto and to close the same, the latter member being provided with a glass or other light transmitting center member whereupon a number may be painted and, by the placement of the light in the interior of the casing, be made visible.

The side wall 4 comprises a frame portion 5, preferably formed of sheet metal. One edge thereof is rolled, as at 6, to accommodate a rod 7 whereby it may be hingedly mounted. The central opening comprised by the frame has formed thereabout a peripheral depressed portion 8 in which may be seated a clear glass member 9 and a frosted glass member 10.

It frequently happens that the combined thickness of the two glass members, or of one glass member, if but one is used, cannot be predetermined, and this is especially true when these side windows must be replaced on the road when they are accidentally broken. It is necessary, therefore, to provide simple means whereby any thickness of glass may be expeditiously seated in the peripheral depressed portion 8.

To this end I form the frame 5 with auxiliary depressed portions 11 which are offset from the peripheral portion, and in this case, of a less depth than the same. In these latter depressed portions I position angle members 12 which are preferably welded to the main frame along their short sides 13, the longer sides 14 being slotted as at 15. Cooperating with these supporting members 12, are angle members 16 having sides 17 adapted to press against and maintain the glass members in the depressed portions 8, and having sides 18 which are slotted at 19. By passing a screw 20 through the slots 15 and 19 and causing washers 21 and 22 to bear against the sides of each of the slots, the tightening 100 of a nut 23 results in the efficient maintenance of the glass in position.

It will be seen from the foregoing description that because of the slot which has its longer dimension perpendicular to the pane 110

of the glass the member 16 may be positioned, within limits, to accommodate any thickness of glass and upon the breakage of such glass it is a matter of but a moment to loosen the movable-angle members and thereafter insert a new glass which will be satisfactorily positioned in the side-wall irrespective of the thickness of the glass members.

Moreover, because of these slots the glass may be removed by simply loosening the bolts 20 and without entirely removing the bolts. This prevents the dropping and consequent loss of these bolts and further admits of the adjustment or change of glasses by but one man who is not compelled to handle the bolts and glasses at the same time. This feature is of particular advantage in railroad practice where repairs must be made in a simple and expeditious manner under rigid service conditions.

Although I have shown but two auxiliary depressed portions, it is, of course, entirely possible that one such portion might be formed on each side of the opening whereby the glass would be maintained at four points. Again, it may be desirable, because of construction or design considerations to position the holding means in a different relationship from those hereinbefore described. All of these variations, of course, come within the scope of the present invention and I desire, therefore, that the same be limited only by the showing of the prior art and by the scope of the appended claims.

Having thus described my invention, what I claim as new and desire to secure by Letters Patent is:

1. A closure member comprising a frame having an opening therein, a peripheral depressed portion formed around said opening, auxiliary depressed portions offset from said peripheral portion, supporting means seated in said auxiliary portions, and means cooperating therewith for securing members in said opening whereby the same seat in said peripheral portion and are held therein irrespective of its thickness.

2. A closure member comprising a frame having an opening therein, a peripheral depressed portion formed around said opening, auxiliary depressed portions offset from, and of a less depth than, said peripheral portion, supporting means seated in said auxiliary portions, and means cooperating therewith for securing members in said opening whereby the same seat in said

peripheral portion and are held therein irrespective of its thickness.

3. A closure member comprising a frame having an opening therein, a peripheral depressed portion formed around said opening, auxiliary depressed portions offset from said peripheral portion, supporting means seated in said auxiliary portions, and members adapted to be adjustably secured to said means for securing a member in said opening whereby the same seat in said peripheral portion and are held therein irrespective of its thickness.

4. A closure member comprising a frame having an opening therein, a peripheral depressed portion formed around said opening, auxiliary depressed portions offset from said peripheral portion, slotted supporting members seated in said auxiliary portions, and cooperative slotted members adapted to be adjustably connected thereto for securing a member in said opening whereby the same seat in said peripheral portion and are held therein irrespective of its thickness.

5. A closure member comprising a frame having an opening therein, a peripheral depressed portion formed around said opening, auxiliary depressed portions offset from said peripheral portion, angle-members having one side seated in said auxiliary portions and the other side slotted, other angle-members of like characteristics having one side slotted, and means for adjustably mounting said last-named angle-members for securing a member in said opening whereby the same seat in said peripheral portion and are held therein irrespective of its thickness.

6. A closure member comprising a frame having an opening therein, a peripheral depressed portion formed around said opening, auxiliary depressed portions offset from said peripheral portion, angle-members having one side seated in said auxiliary portions and the other side slotted, other angle-members of like characteristics having one side slotted, and bolts passing through said slots and so associated with said angle members that, upon the loosening thereof a member held in place thereby may be removed without the total removal of said bolts.

In witness whereof, I have hereunto subscribed my name.

LEE B. JONES.

Witnesses:

J. A. WIEBER,
EDWARD H. WERZNER.

Certificate of Correction.

It is hereby certified that in Letters Patent No. 1,492,988, granted May 6, 1924, upon the application of Lee B. Jones, of Evansville, Indiana, for an improvement in "Number Plates for Headlights," an error appears in the printed specification requiring correction as follows: Page 1, line 57, after the word "closure" and before the period insert the words *door is described as being attached, for example, to a headlight, such as is described in the above identified co-pending application;* and that the said Letters Patent should be read with this correction therein that the same may conform to the record of the case in the Patent Office.

Signed and sealed this 15th day of July, A. D. 1924.

[SEAL.]

THOMAS E. ROBERTSON,
Commissioner of Patents.
